United States Patent Office.

ELIJAH EVANS, OF SPARTA, OHIO.

Letters Patent No. 102,930, dated May 10, 1870.

IMPROVEMENT IN STOVE-LEGS.

The Schedule referred to in these Letters Patent and making part of the same.

To all whom it may concern:

Be it known that I, ELIJAH EVANS, of Sparta, in the county of Morrow and State of Ohio, have invented certain new and useful Improvements in Stove-Leg Fastenings; and I do hereby declare that the following is a full, clear, and exact description thereof, reference being had to the accompanying drawings and to the letters of reference marked thereon, which form a part of this specification.

The nature of my invention consists in the construction and arrangement of a "fastening for stove-legs," as will be hereinafter more fully set forth.

In order to enable others skilled in the art to which my invention appertains to make and use the same, I will now proceed to describe its construction and operation, referring to the annexed drawings, in which—

Figure 1 is a longitudinal vertical section of a stove-leg, showing the manner of fastening the same to the bottom of the stove, and

Figure 2 is a front view of the same.

A represents a portion of the bottom of a stove to which one of the legs is to be fastened.

On the under side of the bottom A, near the outer edge, are placed two lugs *a a*, a suitable distance apart, so that the knee of the stove-leg will fit between them.

A suitable distance in rear of the lugs *a a*, on the under side of the bottom A, is a bar or flange, *b*.

The dovetail formed by the flanges *b* and *f* may, instead of running across the stove-leg, as above set forth, run lengthwise, when the projection *d*, on the bottom of the stove, will be suitably changed, so as to lock or fasten the stove-leg by means of a ball, block, or roller, as described.

To release and remove the stove-leg, it is only necessary to raise the block *h* up, when it can be readily taken out and the stove-leg removed, the rear side of which is inclined downward and toward the rear, as seen in fig. 1. And a short distance in rear of the flange *b* is a projection, *d*, which extends, on the front side, perpendicularly downward.

The stove-leg B is bent, so as to form the knee *e*, which fits in between the lugs *a a*. Its upper portion is then bent slightly downward, and extends toward the rear, having on its upper side a projecting flange, *f*, which is inclined on its front side so as to correspond, and form a dovetail with the inclined flange *b* on the bottom A.

The rear end of the stove-leg is spread downward, and slightly curved toward the lower edge, and has a small projecting flange, *i*, on the sides and lower edge.

When, now, the leg B is placed so that the knee fits in between the lugs *a a*, and the flanges *b* and *f* engage, as shown, a block, or roller, or ball, *h*, is inserted between the rear end of the stove-leg and the projection *d*, which block or roller falls down against the curved portion between the flanges *i i*, and locks the leg firmly in place.

Having thus fully described my invention.

What I claim as new, and desire to secure by Letters Patent, is—

1. The lugs *a a*, flange *b*, and projection *d*, constructed as described, and arranged on the under side of the bottom of a stove, substantially as and for the purposes herein set forth.

2. The stove-leg B, constructed as described, and provided with flange *f*, and its rear end curved and provided with flange *i*, substantially as and for the purposes herein set forth.

3. The combination of the bottom A, having lugs *a a*, flange *b*, and projection *d*, with the stove-leg B, constructed as described, and the block *h* or its equivalent, all substantially as and for the purposes herein set forth.

In testimony that I claim the foregoing as my own, I affix my signature in presence of two witnesses.

ELIJAH EVANS.
